Ebenezer May Jr.
Gutter Patent

The Schedule referred to in these Gutter Patent and making part of the same containing a description in the words of the said Ebenezer May himself of his improvement in the machine for washing and cleansing cloth & clothes &c, called the wash Drum.

All persons to whom these presents shall come. Ebenezer May of Hallowell in the county of Kennebec in the state of Maine brick-Mason sends greeting. Be it known that I the said Ebenezer May have invented & constructed made and applied to use a new and useful machine for the washing, and cleansing of cloth. Clothes and other like substances to be called the wash Drum specified in the words following viz. The said machine consists of a tub or tight box of any convenient form (an oblong square box having been generally used by me as the most convenient form) in which is placed a cylindrical Drum a hollow cylinder, suspended on the sides of the tub or box by an axle fixed firm through its centre being in the manner of a common grind stone at such a distance above the bottom of the tub or box that the periphery of the drum will dip into a convenient depth of water in the tub or box. Above or contiguous to any part of the outer circumference or surface of this large drum a smaller drum a cylinder with a plain or fluted surface and which may be either hollow or solid, but the latter form is preferred for the sake of its greater weight, is suspended by an axle thro' its centre so that the peripheries of the said large and smaller drums may just come in contact, and that the cylindrical surface of the larger drum may put in motion the smaller drum when the former is turned round by a crank. A convenient proportion between the diameters of the two drums will be about three or four to one. Springs either horizontal spiral or of any other convenient form are to be applied to said smaller drum or to the axles of the axle (and which may be done

May 20, 1832

in many different ways) so that when the cloth or clothes to be washed shall pass between the peripheries of the two drums the smaller drum shall rise a little but at the same time be kept pressing down by the force of the spring so as to squeeze the cloth or clothes between the outer surfaces or peripheries of the drums. It is a convenient construction of the machine to prevent the water from being kept around in the operation of washing, to have a box'd cover to match the top of the tub or box, the sides of which should be carried up to such height as that the top of the cover will be above and cover both drums; and then the ends of the axle or quidgoud of the smaller drum may be suspended by a inserted into the side of the box'd cover which cover may be so made as that the same with the smaller drum contained in it may be removed from the top of the tub at pleasure and a sliding door, or lid may be placed on an opening at one end of the box cover for the convenience of turning in water and placing in the clothes. The cloth or clothes to be washed are to be suspended or fastened by some small part or extremity of the clothes while lying on the periphery of the larger drum, by pressing such part or extremity, thro' an oblong aperture or slit in the barrel or outer surface of the drums and then by bringing close and hard upon it a cross bar having arms so affixed as to turn vertically, in front a small bolt on the exterior surface of the barrel or circular ends of the larger drums; and securing the cross bar close down by a button, hook or slope of any kind so that the cross bar shall confine the small part or extremity of the cloth fast in the slit. The exterior of the large drums may be covered by nailing or pinning slats at each end on the peripheries of the circular heads of drums, leaving small spaces or slits between them, or the spaces may be closed, except the slits for inserting the ends of the clothes but the former mode is to be preferred. This machine is operated by confining one extreme or end of the clothes to be washed in the slit of the barrel a periphery of the large hollow drum, or by thus confining several pieces of cloth or clothes on different parts of the exterior of the drum, then turning the drum

of the drum, the clothes are carried round lying on the barrel of the drum and are pressed under the small drum or cylinder suspended in contact with the barrel of the large drum. The springs on the small drum, on the extremities of its axis giving way, the clothes are carried by the rotation of the large drum, between the drums, and the water being thus squeezed out of them they are pressed again down into the water or suds in the tub, and when the large drum has gone once round, the clothes are drawn out of the water, and by continuing the motion, they again pass between the drums, and so on until sufficiently washed: — Or you may turn the crank one way for several turns more or less and then by turning it the other way, the clothes lying on the surface of the large drum will be alternately reversed, first one side up and then the other until washed. You may at any time change the position of the clothes by confining some other or new part thereof in the slit of the drum. The water may be drawn off by a cock or aperture in the side or bottom of the tub and may be turned in at a slide opening in one end of the top cover. In testimony that the above is a true specification of my said machine as above described. I have here set my hand and seal the ninth day of May, in the year of our Lord, one thousand eight hundred and thirty two
